Primary Examiner — Lakiya G Rogers*Assistant Examiner* — Altaira J Swangin(74) *Attorney, Agent, or Firm* — Rosenberg, Klein & Lee(57) **CLAIM**

The ornamental design for a solid state hard disk with flanges, as shown and described.

DESCRIPTION

FIG. 1 is a front view of a solid state hard disk with flanges showing my new design;

FIG. 2 is a rear view thereof;

FIG. 3 is a left side view thereof;

FIG. 4 is a right side view thereof;

FIG. 5 is a top view thereof;

FIG. 6 is a bottom view thereof; and,

FIG. 7 is a top front right perspective view thereof.

The portions of the solid state hard disk with flanges shown in broken lines form no part of the claimed design.
